UNITED STATES PATENT OFFICE.

ARTHUR W. JURADO AND CESARE J. SANTORI, OF LOS ANGELES, CALIFORNIA.

DESIGN FOR A SMOKER'S COMBINATION STAND.

Application filed October 22, 1927. Serial No. 23,854. Term of patent 7 years.

To all whom it may concern:

Be it known that we, ARTHUR W. JURADO and CESARE J. SANTORI, respectively a citizen of the United States and a subject of the King of Italy, and residents of Los Angeles, county of Los Angeles, and State of California, have invented a new, original, and ornamental Design for Smoker's Combination Stand, of which the following is a specification, reference being had to the accompanying drawing, forming part thereof.

Fig. 1 is a top plan view of the article, showing our new design.

Fig. 2 is an elevation.

We claim:

The ornamental design for a smoker's combination stand, as shown.

In witness whereof we have hereunto affixed our signatures.

ARTHUR W. JURADO.
CESARE J. SANTORI.
